[73] Assignee: Fort Wayne Pools, Inc., Fort Wayne, Ind.

[57] CLAIM

[**] Term: 14 Years

The ornamental design for a swimming pool coping having a facia with a compound curvature, as shown and described.

[21] Appl. No.: 76,939

DESCRIPTION

[22] Filed: Sep. 16, 1997

FIG. 1 is a perspective view of a swimming pool coping having a facia with a compound curvature showing my new design;

[51] LOC (6) Cl. 25-01

FIG. 2 is a front view thereof;

[52] U.S. Cl. D25/119; D25/2

FIG. 3 is a rear view thereof;

[58] Field of Search D25/199, 136, D25/119, 2, 41; 52/102, 300; 4/496, 506-507, 510-511

FIG. 4 is an end view thereof, the opposite end view being substantially identical;

FIG. 5 is a top view thereof; and,

FIG. 6 is a bottom view thereof.

The claimed design is broken in the center to indicate indeterminate length.
